UNITED STATES PATENT OFFICE.

WALTER R. THATCHER AND NATHAN W. HUSSEY, OF OSKALOOSA, IOWA.

COW-MILKER.

SPECIFICATION forming part of Letters Patent No. 650,572, dated May 29, 1900.

Application filed November 30, 1898. Serial No. 697,863. (No model.)

To all whom it may concern:

Be it known that we, WALTER R. THATCHER and NATHAN W. HUSSEY, citizens of the United States, residing at Oskaloosa, in the 5 county of Mahaska and State of Iowa, have invented a new and useful Cow-Milker, of which the following is a specification.

The invention relates to improvements in cow-milkers.

10 One object of the present invention is to improve the construction of cow-milkers and to provide a simple, inexpensive, and efficient one adapted to discharge milk directly into an ordinary milk-can and capable of being readily transferred from one can to another.

15 A further object of the invention is to provide a simple and effective teat-cup adapted to afford a broad, yielding, and easy surface 20 to a teat and capable of securing a complete air-tight connection with the same without closing the teat or in any manner retarding the flow of the milk.

25 Furthermore, the invention has for its object to provide an adjustable device adapted to be arranged against a cow's udder to prevent the teat-cup from being drawn upward too far on the teat.

30 Another object of the invention is to enable the operator to see whether the cups are working properly and to enable the device to be easily cleaned.

35 The invention consists in the construction and novel combination and arrangement of parts, as hereinafter fully described, illustrated in the accompanying drawings, and pointed out in the claims hereto appended.

40 In the drawings, Figure 1 is a perspective view of a cow-milker constructed in accordance with this invention, the lid or cover of the can being separated from the body portion to illustrate the construction more clearly. Fig. 2 is an enlarged detail perspective view of one of the teat-cups. Fig. 3 is a longitudinal sectional view of the same. Fig. 4 is a 45 transverse sectional view. Fig. 5 is a detail perspective view of the inner casing or cup proper. Fig. 6 is a similar view of the pneumatic ring or cushion.

50 Like numerals of reference designate corresponding parts in all the figures of the drawings.

1 designates a detachable cover or lid designed to be arranged on a milk-can 2, forming an air-tight connection with the same and 5 carrying an air-pump 3 and a vacuum-gage 4, as clearly illustrated in Fig. 1 of the accompanying drawings. The air-pump 3 has its cylinder extending into the cover or lid about one-half of its length, the operating 60 mechanism being located above the said lid or cover, which is hollow. The lower point of the cylinder extends below the bottom of the lid or cover and projects into the milk-can, so that the air within the same can be 65 exhausted to create a sufficient vacuum for effecting the milking operation. The vacuum-gage is mounted upon the upper end of a short tube 5, which extends through the cover or lid into the can, being provided above the 70 said lid or cover with a valve or stop-cock 6. The gage is adapted to indicate when a sufficient amount of air is exhausted from the can by the air-pump, and in the operation of the milker the air is exhausted from the can before the cups are applied to a cow. 75

The can is provided at one side, near the top, with a stop-cock 7, to which is attached a flexible tube 8, consisting of a rubber hose or other suitable material and designed to be 80 connected with a cow's udder for conducting the milk from the same to the can when the stop-cock 7 is opened. The rubber hose or tube is connected with the udder of the cow by means of four teat-cups 9, which are provided with independent stop-cocks 10. 85

The machine is operated by placing the lid or cover, to which the pump and gage are attached, upon the can and pressing it down to form an air-tight joint. The operating-lever 90 11 of the air-pump is then oscillated until a portion of the air in the can is exhausted, which will be indicated by the gage. When a proper vacuum has been obtained, the stop-cock at the side of the can is opened and the 95 cow's teats are placed one by one in the teat-cups. The stop-cocks of the teat-cups are open, and the milk will flow through the cups and hose into the can.

Each teat-cup consists of an inner casing 100 12 and an outer casing 13, both constructed of rubber, metal, or other suitable material, and the inner casing has its upper end 14 enlarged, forming an annular seat for a pneu-

matic ring 15. The enlargement 14 has a horizontal lower portion or shoulder, and the upper edge 16 is extended inward to form a flange which overhangs and engages the upper face of the pneumatic ring. The flange 16 is curved to conform to the configuration of the ring, which provides a soft, yielding, and easy surface to the teat. The interior diameter of the ring is less than the diameter of the inner casing or that portion of the teat-cup below the seat. The lower end of the inner casing is tapered at 17 and receives and forms a seat for a tapering glass tube 18, which is adapted to extend into a rubber hose 19, constituting a branch of the main hose or pipe 8. This glass is retained in the inner casing by any suitable means to afford an air-tight joint, and while providing an efficient connection between the cup and the hose it also enables the operator to see when the cup is working properly.

The outer casing, which is cylindrical, is adjustably secured to the inner casing by means of a pin 20 and a longitudinal slot 21, the pin being mounted on the inner casing and the slot being formed in the outer casing and having a series of branches or extensions 22, arranged at intervals and adapted to receive the pin, whereby the parts are retained at the desired adjustment. The adjustable outer casing is designed to be arranged against the udder of a cow to prevent a teat from being drawn inward too far into the inner casing. The teat is placed in the cup, and the stop-cock or valve 10 is opened, which causes the teat to be drawn into the opening of the pneumatic ring, making an air-tight joint, without closing the said teat, the outer adjustable section serving as a stop to limit such inward movement. After the point of the teat is inserted in the opening of the pneumatic ring or cushion the outside casing is adjusted up to the udder of the cow and secured by engaging the pin with one of the branches or extensions of the slot, which will insure a proper operation of the device.

The invention has the following advantages: The cow-milker is simple, inexpensive, strong, and durable, it is portable, easy to operate, and easily cleaned, and it keeps the milk and inside of the can absolutely clean. By mounting the operating mechanism on the lid or cover any number of cans may be used with one machine. The pneumatic rubber ring affords a broad and easy surface to the teat, the air-pressure adjusting the rubber to any shape or size, thereby securing a complete air-tight connection without closing the teat or in any manner retarding the flow of the milk. The adjustable telescopic section by pressing against the udder of a cow prevents the inner section or cup proper from being drawn too far up on a teat, and the

transparent tubes enable the operator to see readily how the device is working and whether all the cups are operating properly.

Changes in the form, proportion, and minor details of construction may be resorted to without departing from the spirit or sacrificing any of the advantages of this invention.

What is claimed is—

1. A cow-milker comprising a can having a stop-cock, a removable lid or cover adapted to be applied to different cans, a pump mounted on the removable lid or cover for exhausting air from the can, a vacuum-gage also carried by the lid or cover and communicating with the interior of the can, and a tube having teat-cups and connected with the stop-cock, the latter being adapted to control the passage of air through the tube, whereby the air in the can may be exhausted prior to the operation of milking, substantially as described.

2. A cow-milker provided with a teat-cup comprising an inner teat-receiving section, and an outer section fitting over said inner section and adjustable beyond the teat-receiving end thereof for engagement against the udder of the animal, and fastening means for securing the outer section in its adjusted positions, substantially as described.

3. A cow-milker provided with a teat-cup comprising an inner section or cup proper having its upper end enlarged to form a seat, a cushioning-ring arranged within the enlarged upper end of the inner section, and an adjustable outer section, substantially as described.

4. A cow-milker provided with a teat-cup comprising an inner casing having a tapering lower portion, a transparent tube fitted in the lower portion of the inner casing, a cushion arranged at the upper end of the inner casing, and an adjustable outer casing, substantially as described.

5. A cow-milker provided with a teat-cup having a teat-receiving section, and a separate udder-engaging member adjustable to variable positions beyond the receiving end of said section, substantially as described.

6. In a cow-milker, the teat-cup consisting of an inner casing and an outer casing adjustable with relation to each other, and a pneumatic ring arranged within the outer casing at one end of the inner casing, and having an inner diameter less than the diameter of said inner casing, substantially as described.

In testimony that we claim the foregoing as our own we have hereto affixed our signatures in the presence of two witnesses.

WALTER R. THATCHER.

NATHAN W. HUSSEY.
